UNITED STATES PATENT OFFICE.

JOHN E. JOHNSEN, OF CHICAGO, ILLINOIS.

DRINKING-FOUNTAIN.

1,032,142.

Specification of Letters Patent.

Patented July 9, 1912.

Application filed July 21, 1911. Serial No. 639,742.

To all whom it may concern:

Be it known that I, JOHN E. JOHNSEN, a citizen of the United States, and a resident of the city of Chicago, county of Cook, and State of Illinois, have invented certain new and useful Improvements in Drinking-Fountains, of which the following is a specification.

My invention relates to improvements in sanitary drinking fountains or cups and has for its object the production of a device of this character which will be of improved construction and efficient in operation.

Other objects will appear hereinafter.

With these objects in view my invention consists in the combinations and arrangements of parts hereinafter described and claimed.

The invention will be best understood by reference to the accompanying drawing forming a part of this specification, and in which,

Figure 1 is a central vertical section of a drinking fountain embodying my invention, and Fig. 2 is a transverse section taken on line $\alpha-\alpha$ of Fig. 1.

The preferred form of my construction as illustrated in the drawing comprises an inlet chamber 1 of comparatively large capacity, said chamber being formed by the substantially hemispherical member 2 which bears the inlet opening 3 adapted to be connected with any suitable source of water supply, and the substantially hemi-spherical member 4 which is in threaded connection, as shown, with the member 2. Leading from the chamber 1 is the outlet passage 5 which is formed in the member 4, said passage being screw threaded as shown for the reception of the cup-like member 6 which is threaded therein, the member 6 bearing a restricted discharge opening 7 which leads to the valve chamber 8, the surrounding walls of the latter being formed integral with those of the passage 5. Leading from the valve chamber 8 is the discharge passage 9 which extends vertically, terminating in the nozzle 10 which is threaded to a nipple 10' formed at the upper end of the passage 9. The upper end of the nozzle 10 is preferably enlarged as shown and is provided with a restricted opening 11 which is positioned at the bottom of the cup-shaped or recessed upper end portion of said nozzle. The lower end of the passage 9 is governed by the valve 12 which is formed preferably of rubber, said valve

being mounted on the valve stem 13 which is reciprocally mounted, said valve being adjustably secured in position upon said stem by means of nuts 14 which are threaded upon said stem. The valve 12 is normally held seated, that is in a position closing the passage 9, through the medium of the compression spring 15 which is interposed between the innermost of the nuts 14 and the adjacent end of the member 6. Opening movement of the valve 12 is effected through the medium of the head 16 formed at the outer extremity of the stem 13, depression of said head evidently effecting the desired movement of said valve.

Surrounding the nozzle 10 is a cup 17 which is in threaded connection as shown with the body of the device, said cup being of a form corresponding substantially with that of the nozzle but of greater dimensions so that a considerable space will intervene the adjacent surfaces of said nozzle and cup. The lower end of the cup 17 is in open communication with the upper end or mouth 18 of the drain passage 19, said opening and passage being formed in the body of the device as clearly illustrated in the drawing.

The valve chamber 8 and the discharge passage 9 are in constant communication through the medium of the restricted passage 20. With this provision it will be seen that although the lower end of the passage 9 is closed by the valve 12, a restricted flow of water will be permitted through the passage 20 thereby obviating the possibility of the water in the fountain becoming stagnant and unsanitary, a constant flow being permitted through this provision.

The discharge passage 9 and the drain passage 19 communicate with each other through the opening 21 through which passes the valve stem 13. The opening 21 however is closed by valves 22 and 22', the former being held in position by means of the nut 23 which is threaded upon the stem 13, and the latter by means of a shoulder which is formed upon said stem. Said valves are so positioned that the opening 21 will be closed thereby with the stem 13 at either of its terminals of movement, the valve 22 being adapted to close said opening when said stem is in normal position and the valve 22' to close said passage when said stem is in depressed position. If desired, the valve 22 and accompanying nut 23 thereof may be dispensed with. In this event however the

flow of water when the valve stem is in normal position will not extend up through the passage 9 and nozzle 10, but directly through the lower end of said passage 9 through the opening or passage 21 into the drain passage 19, the flow not being impeded, the course only thereof being changed. Also if desired the passage 20 may be dispensed with in addition to the valve 22 and nut 23. When this is done however, the continuous flow of water through the fountain will be stopped but stagnant water will not be permitted to lodge in the device, since any water remaining in the passage 9 after using the fountain will immediately drain therefrom through the opening 21.

A fountain of the construction set forth, is simple and economical hence may be manufactured at a low cost. The same is durable and because of the simplicity of the construction is not susceptible to readily becoming inoperable. By removably securing the member 6 in position, in the event of the passage therethrough not being suited to the pressure of water which the fountain is used in connection with, said member 6 may be removed and another having an opening of proper diameter arranged in its place. Through the provision of the inlet chamber 1 of large capacity relative to the discharge opening thereof, a constant flow of water at a constant pressure from said chamber upon depression of the valve stem is insured.

While I have illustrated and described the preferred form of construction for carrying my invention into effect, this is capable of variation and modification without departing from the spirit of the invention. I therefore do not wish to be limited to the precise details of construction as set forth, but desire to avail myself of such variations and modifications as come within the scope of the appended claims.

Having described my invention what I claim as new and desire to secure by Letters Patent is:

1. A device of the class described comprising an inlet chamber; a restricted outlet for said chamber; a valve chamber communicating with said outlet; a discharge passage leading from said valve chamber; a nozzle at the outer terminal of said passage; a valve governing said passage; a cup surrounding said nozzle; a drain passage leading from said cup, there being a passage connecting said discharge and drain passages; and a valve operative with said first mentioned valve, for governing said last mentioned passage, said second mentioned valve being so positioned that when said first mentioned valve is in closed position said second mentioned valve will be in open position, and vice versa, substantially as described.

2. A device of the class described comprising an inlet chamber; a restricted outlet for said chamber; a valve chamber communicating with said outlet; a discharge passage leading from said valve chamber; a nozzle at the outer terminal of said passage; an exteriorly projecting valve stem; a normally closed valve on said stem governing said passage; a cup surrounding said nozzle; a drain passage leading from the bottom of said cup, there being a passage establishing communication between said discharge and drain passages; and a valve carried by said valve stem governing said last named passage, said last named valve being arranged to be in open position when said first named valve is in closed position, and vice versa, substantially as described.

3. A device of the class described comprising an inlet chamber; a restricted outlet for said chamber; a valve chamber communicating with said outlet; a discharge passage leading from said valve chamber; a nozzle at the outer terminal of said passage; an exteriorly projecting valve stem; a normally closed valve on said stem governing said passage; a cup surrounding said nozzle; a drain passage leading from the bottom of said cup, there being a passage establishing communication between said discharge and drain passages; a valve carried by said valve stem governing said last named passage, said last named valve being arranged to be in open position when said first named valve is in closed position, and vice versa, substantially as described.

4. A device of the class described comprising an inlet chamber; a restricted outlet for said chamber; a valve chamber communicating with said outlet; a discharge passage leading from said valve chamber; a nozzle at the outer terminal of said passage; an exteriorly projecting valve stem; a normally closed valve on said stem governing said passage; a cup surrounding said nozzle; a drain passage leading from the bottom of said cup, there being a passage establishing communication between said discharge and drain passages; and two valves carried by said valve stem governing said last mentioned passage, said valves being adapted to act alternately to close said passage at either terminal of movement of said valve stem, substantially as described.

5. A device of the class described comprising an inlet chamber; a restricted outlet for said chamber; a valve chamber communicating with said outlet; a discharge passage leading from said valve chamber; a nozzle at the outer terminal of said passage; an exteriorly projecting valve stem; a normally closed valve on said stem govern-

ing said passage; a cup surrounding said nozzle; a drain passage leading from the bottom of said cup, there being a passage establishing communication between said 5 discharge and drain passages; two valves carried by said valve stem governing said last mentioned passage, said valves being adapted to act alternately to close said passage at either terminal of movement of said 10 valve stem; and a restricted unobstructed

passage establishing communication between said valve chamber and said discharge passage, substantially as described.

In testimony whereof I have signed my name to this specification in the presence of two subscribing witnesses.

JOHN E. JOHNSEN.
